6 Claims. (Cl. 328—60)

(Granted under Title 35, U.S. Code (1952), sec. 266)

The invention described herein may be manufactured and used by or for the Government of the United States of America for governmental purposes without the payment of any royalties thereon or therefor.

The present invention relates to a random permutation generator and more particularly to a random permutation generator in which no number is repeated in a given set until all of the numbers in the set have been selected.

The prior art random permutation generators have in the main had for their prime mission a random generator with the quality of complete fortuity i.e. no one number in the set was more likely to come up than any other number. A generator of this type is disclosed in U.S. Patent No. 2,767,315 by L. Costen which issued October 16, 1956. The Costen circuit yields a random digit where one digit has no more chance of coming up than any other digit in the set. By definition, however, complete fortuity also includes the possibility of the repetition of one or more numbers and this quality is desirable for the purposes for which the Costen generator was designed.

There has been a long felt need, however, for a random digit generator or random permutation generator in which there exists an exception to the complete fortuity desired in the Costen digit generator. This exception is in the non-repetition of a number of a given set until all of the numbers of the set have been chosen. Thus, in certain instances a complete scan of a given set is required with no repetition before the next set is started to insure that each position or number is utilized the same number of times. One such use would be in the random scanning of a radar antenna. Here it is desirable that the entire area be scanned periodically, but in some instances it is also desirable that given sectors of the area are scanned in random order.

According to the invention, a random width pulse generator is triggered by a clock pulse. The random width pulse generator is then utilized to gate a shift pulse generator, the output of which shifts a circulating storage means such as a shift register with a given number of stages, the number of stages equal to the number of conditions in the permutation. One of the stages of the shift register is set at condition 1 and the others at condition 0. Thus, the condition 1 is shifted around the shift register with the output of the shift pulse generator. When the shift pulse generator stops after its gate is closed by the random pulse width generator, the stage with the 1 stored is a completely randomly selected stage, which corresponds to 1 condition. At this point a readout pulse reads out all of the stages of the shift pulse generator and that condition is sensed. Each stage of the shift register has a bistable multivibrator associated therewith. At the time of readout the bistable multivibrator associated with that stage having a 1 stored therein is triggered to its opposite state shorting that stage out to avoid ambiguity in the next readout. A counter counts the number of readouts, and when the number of readouts equals the number of stages in the shift pulse register, all of the multivibrators are reset to their original condition and the cycle repeats itself.

It is thus an object of the present invention to provide

2

a random permutation generator having a predetermined number of possible conditions to be sensed.

Another object of the present invention is to provide a random permutation generator in which all of the possibilities of a given set are sensed before any one possibility can be repeated.

A further object of the invention is a provision of the random permutation generator which requires a minimum of adjustment.

Yet another object of the present invention is to provide a random permutation generator which is simple, automatic in operation and relatively inexpensive.

A still further object of the present invention is to provide a random permutation generator in which the number of possible conditions can be varied with a minimum of modification.

These and other objects of the present invention will become more readily apparent with reference to the following detailed description taken in conjunction with the drawings in which the sole figure is a block diagram of a preferred embodiment of the present invention.

Referring to the drawing there is shown input terminal 11 connected to counter 12 and random width pulse generator 13. The pulse generator 13 comprises a thyratron noise generator 49 which is coupled through an amplifier 50 to a pulse generator 51. The thyratron noise generator 49 produces a random noise-electrical output which is amplified and used to modulate the waveform of the pulse generator 51. The random-width pulse generator 13 is disclosed in co-pending application Serial No. 170,287, filed January 31, 1962, Random Number Generator. Input terminal 11 is also connected to coincidence gates 14, 16, 17, 18, 24, 26, 27, and 28. Coincidence gates 24, 26, 27 and 28 are connected to bistable multivibrators 34, 36, 37 and 38 respectively. The output of random width pulse generator 13 is connected to shift pulse generator 15, the output of which is connected to shift register stages 44, 46, 47 and 48. Counter 12 has its outputs connected to coincidence gate 20, the output of which is connected to one input of bistable multivibrators 34, 36, 37 and 38. Output 47i of shift register stage 47 is connected to one input of coincidence gates 17, 47b and 47c and 47d. Output 47j of shift register stage 47 is connected to one input of coincidence gate 47f and 47g. Output 47i of shift register stage 48 is connected to one input of coincidence gates 18, 48b and 48d. Output 48j of shift register stage 48 is connected to one input of coincidence gates 48e and 48g. The output 44i of shift register stage 44 is connected to one input of coincidence gates 14, 44b and 44d. The output 44j of shift register stage 44 is connected to one input of coincidence gates 44e and 44g. The output 46i of shift register stage 46 is connected to one input of coincidence gates 16, 46b and 46d. The output 46j of shift register stage 46 is connected to one input of coincidence gates 46e and 46g.

Output 37a of multivibrator 37 is connected to one input of coincidence gates 47a and 47h and to a second input of coincidence gates 47d and 47g. Output 37b of multivibrator 37 is connected to one input of coincidence gates 47c and 47f and a second input of coincidence gates 47d and 47e. Output 38a of multivibrator 38 is connected to one input of coincidence gates 48a and 48h and a second input of coincidence gates 48b and 48g. Output 38d of multivibrator 38 is connected to one input of coincidence gates 48c and 48f and a second input of coincidence gates 48d and 48e. Output 34a of multivibrator 34 is connected to one input of coincidence gates 44a and 44h and a second input of coincidence gates 44b and 44g. Output 34b of multivibrator 34 is connected to one input of coincidence gates 44c and 44f and a second input of coincidence gates 44d and 44e. Output 36a of multivibrator

36 is connected to one input of coincidence gates 46a and 46h and a second input of coincidence gates 46b and 46g. Output 36b of multivibrator 36 is connected to one input of coincidence gates 46c and 46f and a second input of coincidence gates 46d and 46e.

The outputs of coincidence gates 46a and 46b are connected together and to a second input of coincidence gates 47a and 47c. The outputs of gates 46c and 46d are connected together and form one input of shift register stage 47. The outputs of coincidence gates 46e and 46f are connected together and form a second input of shift register stage 47. The output of coincidence gates 46g and 46h are connected together and form a second input of coincidence gates 47f and 47h.

The outputs of coincidence gates 47a and 47b are connected together and form a second input of coincidence gates 48a and 48c. The outputs of coincidence gates 47c and 47d are connected together and form one input of shift register stage 48. The outputs of coincidence gates 47e and 47f are connected together and form a second input of shift register stage 48. The outputs of coincidence gates 47g and 47h are connected together and form a second input of coincidence gates 48f and 48g.

The outputs of coincidence gates 48a and 48b are connected together and form a second input of coincidence gates 44a and 44c. The outputs of coincidence gates 48c and 48d are connected together and form one input of shift register stage 44. The outputs of coincidence gates 48e and 48f are connected together and form a second input to shift register stage 44. The outputs of coincidence gates 48g and 48h are connected together to form a second input of coincidence gates 44f and 44h.

The outputs of coincidence gates 44a and 44b are connected together and form a second input of coincidence gates 46a and 46c. The outputs of coincidence gates 44c and 44d are connected together and form one input of shift register stage 46. The outputs of coincidence gates 44e and 44f are connected together and form a second input to shift register stage 46. The outputs of coincidence gates 44g and 44h are connected together and form a second input to coincidence gates 46f and 46h.

The outputs of coincidence gates 46a and 46b are connected together and form a second input of coincidence gates 47a and 47c. The outputs of coincidence gates 46c and 46d are connected together to one input of shift register stage 47. The outputs of coincidence gates 46e and 46f are connected together to a second input of shift register stage 47. The outputs of coincidence gates 46g and 46h are connected together and to a second input of coincidence gates 47f and 47h.

Operation

In operation an evenly spaced clock pulse is introduced to input terminal 11 which provides an input to counter 12 and random-width pulse generating means 13. The clock pulse at input terminal 11 also provides enabling signals to coincidence gates 16, 17, 18, 14, 24, 26, 27, and 28. Upon receipt of a clock pulse, random-width pulse generator 13 produces a pulse at its output which is utilized to gate shift pulse generator 15. Shift pulse generator 15 then puts out a series of evenly spaced pulses, the number of which depending upon the width of the gate received from the random-width pulse generator 13. Stages 44, 46, 47 and 48 form a circulating shift register which is shifted one stage with each pulse received from shift pulse generator 15. One of the stages of the circulating shift register is set at one and the rest are set at zero. Thus, the one will circulate through the stages until the random-width pulse generator 13 gates shift pulse generator is off, at which time the entire system will wait for the next clock pulse at terminal 11. Bistable multivibrators 34, 36, 37 and 38 each have outputs controlling the coincidence gates at the outputs of the circulating shift register stages i.e. each multivibrator output controls the output for one associated shift register stage. Multivibrator 34 has outputs 34a and 34b which enable the associated coin-

5 cidence gates 44a through 44h at the outputs of shift register stage 44. Multivibrator 36 similarly controls the outputs of shift register stage 46 through its associated coincidence gates 46a through 46h. Multivibrator 37 through its outputs 37a and 37b control the outputs of shift register stage 47 through its associated coincidence gates 47a through 47h, and multivibrator 38 controls through its outputs 38a and 38b the outputs of shift register stage 48 through its associated coincidence gates 48a through 48h.

10 Assume that shift register stage 47 has a set input or is at the one state and shift register stages 46, 48 and 44 are all at the 0 state. Further assume that an input clock pulse at terminal 11 will then enable all coincidence gates 14, 16, 17 and 18 together with coincidence gates 24, 26, 27 and 28 to yield an output providing there is an information pulse present at the other input of these gates. Thus, if stage 47 has a one therein, coincidence gate 17 will yield a one at its output and at this point multivibrator 36 will be triggered to its opposite state. The other coincidence gates 14, 16 and 18 will all yield zeros since there will be no information pulse at their inputs and thus the first number read out will be a 0 from gates 24, 27 and 28 will not yield an output to their respective multivibrators since there will be no information pulse at their inputs. In this state multivibrators 34, 37 and 38 will have an enabling signal at outputs 34b, 37b and 38b respectively. Upon receipt of a circulating or a shift pulse at this point stages 44, 47 and 48 of the shift register 15 will then pass their signal to the next stage of the shift register through coincidence gates 44d, 44e, 47d, 47e, and 48d and 48e. The output of shift register 46, however, cannot be passed through 46d and 46e since an enabling pulse is not present on output line 36b from multivibrator 36. Instead an enabling output is present at 36a which passes the outputs of shift register stage 46 through gates 46b and 46g to the inputs of gates 47b, 47c and 47f and 47h, bypassing stage 47. Hence, upon the next random-width pulse from pulse generator 13 and consequently the next series of shift pulses from shift pulse generator 15, stage 47 will be bypassed and the one, previously in stage 47, will be circulated through stages 48, 44 and 46. At this time also counter 12 has made a 1 count and on the next clock pulse at terminal 11 will register a 2 count. After all of the possible locations of the circulating 1 are used up, every multivibrator 34, 36, 37 and 38 will be in the condition described with respect to multivibrator 36 i.e. the enabling pulse will be from the (a) terminal and at that time counter 12 will have counted the number of stages in the circulating shift register. Gate 20 is at that time receiving an enabling pulse at all of its inputs resulting in a reset pulse at the output thereof which is coupled to multivibrators 34, 36, 37 and 38 resetting all the multivibrators to their original condition i.e. with an enabling output at their (b) terminals 34b, 36b, 37b, and 38b. 20 This results in an enabling pulse being coupled to coincidence gates 46d, 46e, 47d, 47e, 48d, 48e, 44d and 44e. Each stage is then coupled through its respective coincidence gates to the following stage to start the permutation cycle over again with the next clock pulse at input terminal 11.

25 30 Obviously many modifications and variations of the present invention are possible in the light of the above teachings. Any desired number of shift register stages can be utilized, for example, together with the associated circuitry, as dictated by the number of conditions in a given set. It is therefore to be understood that within the scope of the appended claims the invention may be practiced otherwise than as specifically described.

35 40 What is claimed is:

45 50 1. A random permutation generator comprising: an input terminal; means connected to said input terminal for generating a random number of shift pulses, circulating storage means having a serial storage stages,

each of said stages connected to said shift pulse generating means, said storage means operable to shift stored information one stage upon receiving a shift pulse,
 a plurality of bypass means, each of said serial storage stages having an output connected to a different one of said bypass means, all of said bypass means connected to said input terminal, each of said bypass means operable to bypass the stages following the stage connected thereto upon coincidence of an output from said storage stage and a clock pulse, 5
 a plurality of read-out means each of said read-out means connected to said input terminal and an output of a different one of said stages, each of said read-out means operable to yield a signal at its output upon the coincidence of an output from said storage and a clock pulse, 10
 2. A random permutation generator comprising:
 an input terminal adapted for connection to clock pulse means,
 a random width pulse generating means having an input connected to said input terminal, said random width pulse generating means operable to produce a pulse of random width in response to an input pulse, 20
 shift pulse generating means having an input connected to said variable width pulse generating means, said shift pulse generating means operable to produce shift pulses during the period of said random-width pulse, 25
 circulating storage means having a serial storage stages, each of said stages connected to said shift pulse generating means, said storage means operable to shift stored information one stage upon receiving a shift pulse,
 a plurality of bypass means, each of said serial storage stages having an output connected to a different one of said bypass means, all of said bypass means connected to said input terminal, each of said bypass means operable to bypass the stages following the stage connected thereto upon coincidence of an output from said storage stage and a clock pulse, 30
 a plurality of read-out means each of said read-out means connected to said input terminal and an output of a different one of said stages, each of said read-out means operable to yield a signal at its output upon the coincidence of an output from said storage and a clock pulse, 35
 3. A random permutation generator comprising:
 an input terminal adapted for connection to clock pulse means,
 a random width pulse generating means having an input connected to said input terminal, said random width pulse generating means operable to produce a pulse of random width in response to an input pulse, 50
 shift pulse generating means having an input connected

to said variable width pulse generating means, said shift pulse generating means operable to produce shift pulses during the period of said random-width pulse,
 circulating storage means having n serial storage stages, each of said stages connected to said shift pulse generating means, said storage means operable to shift stored information one stage upon receiving a shift pulse,
 a plurality of bypass means, each of said serial storage stages having an output connected to a different one of said bypass means, all of said bypass means connected to said input terminal, each of said bypass means operable to bypass the stages following the stage connected thereto upon coincidence of an output from said storage stage and a clock pulse,
 a plurality of read-out means each of said readout means connected to said input terminal and an output of a different one of said stages, each of said read-out means operable to yield a signal at its output upon the coincidence of an output from said storage and a clock pulse,
 reset means having an input connected to said input terminal and an output connected to each of said bypass means, said reset means operable to reset all of said bypass means upon receiving clock pulses.
 4. The random permutation generator of claim 3 wherein each of said bypass means comprises a bistable multivibrator connected to one input of an AND gate, 30
 another input of said AND gate connected to an output of one of said storage stages, and an output of said AND gate connected to the storage stage following said one of said storage stages.
 5. The random permutation generator of claim 2 35 wherein each of said bypass means comprises a bistable multivibrator connected to one input of an AND gate, another input of said AND gate connected to an output of one of said storage stages, and an output of said AND gate connected to the storage stage following said one of said storage stages.
 6. The random permutation generator of claim 1 40 wherein each of said bypass means comprises a bistable multivibrator connected to one input of an AND gate, another input of said AND gate connected to an output of one of said storage stages, and an output of said AND gate connected to the storage stage following said one of said storage stages.
